(57) CLAIM

The ornamental design for a catheter clamping device, as shown and described.

DESCRIPTION

FIG. 1 is an upper perspective view of a catheter clamping device showing our new design;

FIG. 2 is a lower perspective view thereof;

FIG. 3 is a front side elevational view thereof;

FIG. 4 is a right side elevational view thereof;

FIG. 5 is a rear side elevational view thereof;

FIG. 6 is a left side elevational view thereof;

FIG. 7 is a top plan view thereof; and,

FIG. 8 is a bottom plan view thereof.

The broken line showing in FIGS. 1 and 7 are for illustrative purposes only and forms no part of the claimed design.
